UNITED STATES PATENT OFFICE

FRANK YAHN, OF ST. PETERSBURG, FLORIDA

FRUIT CORER

Application filed February 27, 1931. Serial No. 518,808.

My invention relates to fruit corers and particularly to corers for grapefruit, oranges, apples and the like.

An object of the invention is to provide a corer of extremely simple and cheap construction which will efficiently remove the cores from halved fruit without puncturing the rind.

Another object is to provide such a device with several sizes of cutters for use in coring different sizes of fruit.

A further object of the invention is to provide a core remover which will lift the core bodily from the fruit, one from which the core can be readily extracted and which can be readily dismantled for cleaning.

Other important objects and advantages of the invention will become apparent during the course of the following detailed description when read in conjunction with the accompanying drawings, which form a part of this specification and in which:

Figure 1 is a side elevation of a corer embodying my invention;

Fig. 2 is a bottom plan view thereof;

Fig. 3 is a sectional view taken on the line 3—3 of Fig. 2;

Fig. 4 is a sectional view taken on the line 4—4 of Fig. 3;

Fig. 5 is a view similar to Fig. 3, but showing different sized cutter;

Fig. 6 is a bottom plan view of a modified form of the invention; and

Fig. 7 is a sectional view taken on the line 7—7 of Fig. 6.

Referring now more particularly to the drawings, wherein like numerals refer to like parts throughout the same, 10 indicates a handle which may be made of wood or any other suitable material and the grip portion of which may take any desired form. The handle 10 terminates in a circular base portion 11, the outer face of which is rabbeted as at 12 to form an annular shoulder 13.

45 A cylindrical cutter member 14 has one end received within the rabbeted portion 12 and over the shoulder 13 as clearly shown in Figs. 5 and 7. If desirable suitable fastening means such as a pin and bayonet slot may be employed to lock the cutter to the handle, but

a frictional engagement has been found satisfactory. The edge of the free end of the cutter member 14 is suitably sharpened as at 15.

For the purpose of aiding in the lifting 55 of the core from the fruit, a pointed pin 16 is provided. The pin 16 extends at an angle from the lower face of the base 11 and within the space enclosed by the cutter 14. An angularly disposed socket 17 is formed in the 60 base so that the pin can be readily inserted therein or extracted therefrom. The pin preferably extends a short distance below the edge of the cutter and the pointed end thereof is also spaced inwardly from said edge. 65

In order to provide for the accommodation of cutters of lesser diameter when operating upon smaller fruit, the base 11 is provided with an annular recess or socket 18 in the lower face thereof, producing an annular shoulder 19 which forms a seat for the end of a cylindrical cutter 20. A pointed pin 21 similar in construction and relative arrangement to the pin 16 is removably disposed in an angular socket 22 when 70 the cutter 20 is to be used. In practice only one pin is actually needed, the same being transferred from one socket to another depending on the cutter to be used. 75

In the form of the invention shown in 80 Figs. 6 and 7, instead of using a single diagonal pin 16 or 21, I employ a plurality of vertically disposed pins 23 centrally grouped with respect to the cutters and adapted to penetrate the core. In this form, the handle 85 24 is identical in construction to the handle 10 except that the sockets for the pins 23 are parallel with the sides of the cutters.

In the operation, the cylindrical cutter of 90 correct size is placed on the handle and the pin inserted in the appropriate socket. The cutter is then placed over the end of the core and pressed down to sever the sides of the core from the fruit, the pin meanwhile penetrating the body of the core. When the cutting edge has reached the rind or skin around the core, the device is rotated so as to twist the end of the core free from the rind, whereupon the corer carrying the core is lifted 95 free of the fruit. The cutter is then re- 100

removed from the handle and the core discarded. By making the cutters removable from the handle, cleaning of the device is greatly facilitated which is very important when coring grapefruit and oranges.

The operation of the modified form of the invention is substantially the same as above except the pins do not have to be changed to accommodate different sized cutters.

10 Although a preferred embodiment of the invention has been shown and described, it will be understood that changes in the details of construction may be made without departing from the spirit of the invention as defined by the appended claims.

I claim:

1. A corer comprising a cylindrical cutter and a pin member extending substantially entirely through the bore of said cutter and 20 diagonally thereof.

2. A corer comprising a handle, a cylindrical cutter element carried thereby, and a plurality of pin elements extending longitudinally of and substantially entirely 25 through the bore of said cutter.

3. A corer comprising a handle having a circular base, an annular shoulder formed with said base, a cylindrical cutter having one end received on said shoulder and the 30 other end sharpened, and a diagonally extending pin element carried by said base and extending into the bore of said cutter for substantially the length thereof.

FRANK YAHN.
